UNITED STATES PATENT OFFICE.

JOSIAH K. PROCTOR, OF PHILADELPHIA, PENNSYLVANIA, ASSIGNOR TO THE
PHILADELPHIA TEXTILE MACHINERY COMPANY, OF SAME PLACE.

DESIGN FOR AN ARCH FOR GARNET-MACHINES.

SPECIFICATION forming part of Design No. 34,142, dated February 26, 1901.

Application filed January 8, 1901. Serial No. 42,559. Term of patent 14 years.

To all whom it may concern:

Be it known that I, JOSIAH K. PROCTOR, a citizen of the United States, residing in Philadelphia, Pennsylvania, have invented and produced a certain new and original Design for the Arch of a Garnet-Machine, of which the following is a specification.

My design for the arch of a machine for combing fibrous material and known as a "garnet-machine" is fully illustrated in the accompanying drawings, in which—

Figure 1 is a perspective view of the arch; and Fig. 2 is a section on the line 2 2, Fig. 1.

The essential feature of the design is the arch having a flange with notches in its edge.

A is the arch, curved, as shown in the draw-

ings, and having feet a^3 . An internal flange a extends from one edge of the arch and an external flange a' projects from the opposite edge. In the external flange a' are the series 20 of notches a^2 .

I claim—

The design for the arch of a garnet-machine, as herein described and as illustrated in the accompanying drawings.

In testimony whereof I have signed my name to this specification in the presence of two subscribing witnesses.

JOSIAH K. PROCTOR.
